DICTATING MACHINE

Joseph M. Lucarelle and John E. Renholdt,
Bridgeport, Conn., assignors to Dictaphone
Corporation, New York, N. Y., a corporation
of New York

Original application June 7, 1929, Serial No.
369,044. Divided and this application Novem-
ber 2, 1933, Serial No. 696,364. Renewed Jan-
uary 9, 1936

4 Claims. (Cl. 274—17)

This invention relates to dictating machines, and more particularly to ejector locking devices for dictation machines.

One of the objects thereof is to provide in a machine of the above character a simple, practical and reliable means for preventing manipulation of the record-ejector while the sound-box occupies an operative position relative to the mandrel and record-cylinder. A further object is to provide practical means adapted to permit or prevent operation of a record-ejector irrespective of the position along its path of travel which the sound-box carriage may chance to occupy. Other objects will be in part obvious and in part pointed out hereinafter.

For a further disclosure of the invention, reference may be had to the following description and to the accompanying drawings showing one embodiment of the invention selected merely for purposes of illustration, and in which:

Fig. 1 is a top plan view of a dictating machine with operating parts in the position they assume when the sound-box control is in neutral position;

Fig. 2 is a rear elevation showing the operating parts in the position they assume when the machine is in neutral condition;

Fig. 3 is a sectional view taken substantially on line 3—3 of Fig. 2, with portions of the carriage broken away and other parts shown in section, showing the sound-box control in neutral condition;

Fig. 4 is a diagrammatic view of certain of the operating parts in the position they assume when the sound-box control is moved forwardly into recording position;

Fig. 5 is a diagrammatic view similar to Fig. 4, but shows the operating parts in the position they assume when the sound-box control is moved rearwardly into reproducing position.

This application is a division of our copending application Serial No. 369,044, filed June 7, 1929, now Patent No. 1,968,649, granted July 31, 1934.

The dictating machine selected for the purpose of illustrating the present invention, comprises a main frame 10 having an integral left-hand or head-end standard 11 and a right-hand standard 12. A housing 13 is also made integral with the main frame and provides a suitable bearing for a mandrel shaft 14 supporting at its outer end a mandrel 15, upon which a record cylinder 16 is moved for recording and reproducing. The opposite end of the mandrel shaft supports a driving pulley 17 which is rotated through suitable con-

nection by an electric motor or other prime mover, not shown.

A sound-box carriage 18 is slidably mounted so as to travel longitudinally of the record-cylinder 16 upon the upper tubular guide rod 19 and lower guide rod 20 extending between the left-hand standard 11 and right-hand standard 12. A stylus position or sound-box control lever 21 is rotatably mounted on the carriage rod 19 within an open space 22 formed in the carriage 18 and has a limited range of rotative movement. As shown in Fig. 3, the sound-box control lever 21, or ring lever as it is commonly called in the art, is selectively movable to three stations, namely, recording, neutral and reproducing. When the said lever is in neutral position, as shown in Fig. 3, a lug 23 thereon engages a feed-nut 24 and moves it downwardly out of engagement with a feed-screw 25 extending longitudinally within the guide rod 19. In this position of the feed-nut the operator can freely move the carriage by hand longitudinally of the record-cylinder into any desired position. By shifting the ring lever into either recording or reproducing position, shown by dot and dash outline in Fig. 3, the feed-nut 24 becomes free to be lifted upwardly into engagement with the feed-screw under the influence of the compression spring 26 progressively to advance the carriage when the feed-screw is rotated.

The carriage 18 comprises a casing 28, within which is slidably mounted a sleeve 29 having a hook and slot connection 31 with a link 30, which link is pivotally secured to the ring lever 21. The sound-box 27 is provided with a recording stylus 32 and a reproducing stylus 33, connected in a well known manner to a single diaphragm, not shown. The sound-box tube 34, which supports the sound-box 27, is connected by means of a ball-and-socket joint and a pivot pin connection 36 with a tube 35 slidably mounted within the casing 28. This connection gives the sound-box a limited range of up and down movement in order that it may accommodate itself to record-cylinders of various diameters, or to compensate for any eccentricity or runout of said cylinders. In Fig. 3, these parts are shown in neutral position, in which relation a cam lug 37 on the sound-box tube 34 rides upon an adjustable guide plate 38, raising the sound-box to an inoperative position, with both stylus out of engagement with the record-cylinder. This conditioning is necessary in order to safely load and unload the mandrel 15, and also to allow forward and back spacing of the carriage without marring the record-cyl-

inder surface, as would occur if either of the stylus were left in engagement with the record.

In a similar manner, the sound-box 27 is conditioned for recording when the control lever 21 is moved to the forward position, as shown in Fig. 4, for in this operation the connecting link 30 moves the sleeve 29 rearwardly within the casing 28, and by this movement the cam lug 37 moves out of engagement with the guide plate 38, and 10 allows the recording stylus to engage the record-cylinder. Also, by moving the control lever 21 to the rearmost position, as shown in Fig. 5, the sleeve 29 is moved forwardly within the casing 28 and moves the pivotally connected sound-box forwardly until the lug 37 rides out of engagement 15 with the guide plate 38, and allows the reproducing stylus to engage the sound grooves on the record-cylinder, when matter previously recorded will be audibly reproduced. This form of sound-box control and construction is more fully described in the United States Patent to Bodine et al., No. 1,606,744, November 16, 1926.

When the machine is in operation the mandrel rotates while the carriage moves longitudinally thereof, in order that the stylus may cut or follow a spiral sound groove on the surface of the record-cylinder. It is customary, in a well known manner, to provide a clutch for starting and stopping rotation of the mandrel shaft and feed-screw, so that the operator may instantly control the operation of the machine so as not to use up space on the record-cylinder should he pause in his dictation.

The feed-screw 25 is rotated when the mandrel shaft is set in motion by means of any suitable system of gearing, disposed within the housing. As this gearing is common to many forms of dictation machines, no further description of it will be given herein, nor is it thought necessary to 40 complicate the drawings by the addition of gearing pitch lines.

An ejector is provided for moving the record-cylinder from the mandrel. In its present form it comprises a plunger 64 slidably mounted within the housing 13 for movement longitudinally of the machine. The operating end of the plunger has a head 64', so shaped and disposed as to pass by the flange 65 of the mandrel and to engage the inner end of the record-cylinder 16 when the plunger is advanced. The other end of the plunger is fixed to an upstanding arm 66, forming part of a link 67. The link extends longitudinally of the machine beneath the base of the frame and terminates at a convenient point 55 adjacent the end of the mandrel, where it has pivotal attachment to a transversely disposed lever 68 by means of a screw 69. The lever 68 is fulcrumed upon a stud 70 at the rear of the machine and at its forward end is provided with an upwardly extending portion 71, forming a finger-piece by means of which the lever may be operated. This finger-piece extends through a slotted plate 72 covering a suitable opening 73 left in the casting forming the base 10. The ends of 65 the slot in the plate 72 serve as stops for limiting the movement of the lever.

The ejector parts just described are normally held retracted by means of a spring 73' interposed between and connected to the link 67 and the lever 68 at points adjacent to the screw 69, in which position the ejector is kept out of engagement with the record-cylinder.

Novelty is not claimed for the features of the dictating machine hereinbefore described, and 75 only such detail has been presented as will give a

ready understanding of the present invention and the structural and functional relation thereof to the other parts of the machine, as will now be described.

By the present invention means are provided 5 for automatically rendering the record-ejector inoperative whenever the sound-box control stands in other than neutral position. Thus the record-ejector cannot be moved to eject a record while either stylus is in contact with the record 10 blank.

The means for thus preventing movement of the record-ejector is under control of the sound-box control lever in all positions of the carriage relative to the record-support and comprises a 15 ball 88 mounted for oscillating movement with respect to the carriage rod 20, from which it is suspended by means of hangers 85 and 89 loosely mounted on said rod.

To move the ball 88 to any one of the three positions shown in Figs 3, 4 and 5, a link 90 is provided, connected at one end with the sound-box sliding tube link 30, as by the pin 91, and extending rearwardly and downwardly to a point of connection by means of a stud 92 with the upper 25 end of a lever 93, pivotally mounted on a stud 94 upon the side of the carriage guide support 95. The lower end of said lever occupies an operative position relative to the ball 88, which is yieldingly maintained in engagement therewith by means of a bell crank lever 96 having a longitudinally disposed arm 97 positioned above the base 10, and a transversely disposed arm 98 situated below the base, both of which arms are affixed to a pin 99 extending downwardly through said base. 30 As may best be seen in Fig. 1, this bell crank lever is normally held in contact with the ball 88 by means of a tension spring 100 fastened at one end to the transverse arm of the bell crank, and at the opposite end to a stud 101 on the under- 40 side of the frame. The bell crank is operatively connected with an ejector lock or latching member as will now be described.

As is best shown in Fig. 1, the bell crank 96, which is at all times in operative engagement 45 with the ball 88, is provided with a pin 104 which rides in the V-shaped aperture 105 formed in a latch lever 106 pivotally mounted by a stud 107 on the underside of the base. The latch lever 106 is provided at its outer end with a hook or 50 catch 108 adapted to swing into the path of a pin 109, projecting downwardly from the ejector lever 68. This arrangement of parts is such that the ejector may be operated only when the machine is in neutral condition, that is, when both the 55 recording and reproducing styli are out of engagement with the record-cylinder, and positively locks the record-ejector against operation when the machine is in either recording or reproducing position.

As shown in Fig. 1, the pin 104 in the end of the bell crank arm 98 is in the position it assumes when the sound-box control lever 21 is in neutral position, and when so positioned, the pin being in the high point of the inverted V-shaped 65 slot 105, holds the latch lever 106 in such a position that the hook 108 clears the pin 109 on the ejector lever 68 and does not lock the record-ejector, but when the control lever is moved into either its recording or reproducing station, the 70 pin 104 travels to one or the other of the low points of the inverted V slot 105 and causes the latch lever 106 to lock the ejector lever and positively prevent operation of the ejector.

It will thus be seen that the ball 88 of the 75

present invention serves to condition the record-ejector lock, in predetermined relationship with the stationing of the sound-box control lever 21, regardless of the position of the carriage 18 longitudinally of the machine.

5 As various embodiments might be made of this invention, and as various changes might be made in the construction herein described, all without departing from the scope of the invention, it is 10 to be understood that all matter herein set forth or shown in the accompanying drawings is to be interpreted as illustrative and not in a limiting sense.

We claim:

15 1. In a dictating machine, in combination, a record-support, a carriage, a sound-box supported by said carriage, a sound-box control having recording, neutral and reproducing positions, a record-ejector, means for preventing operation of said record-ejector, means rockable in any position of the carriage for controlling operation of said preventing means, and means pivotally connected to said sound-box control for so controlling movement of said rockable means 25 as to prevent operation of said record-ejector when said sound-box control is moved to reproducing position.

2. In a dictating machine, in combination, a record-support, a carriage, a sound-box supported by said carriage, a sound-box control having recording, neutral and reproducing positions, a record-ejector, means for preventing operation of said record-ejector, means rockable in any position of the carriage for controlling operation of said preventing means, and means piv- 30

35 otally connected to said sound-box control for so controlling movement of said rockable means as to prevent operation of said record-ejector when said sound-box control is moved to recording position.

3. In a dictating machine, in combination, a record-support, a carriage, a sound-box supported by said carriage, a sound-box control having recording, neutral and reproducing positions, a record-ejector, means for preventing operation 10 of said record-ejector, means rockable in any position of the carriage for controlling operation of said preventing means, and means pivotally connected to said sound-box control for so controlling movement of said rockable means as to 15 permit operation of said record-ejector when said sound-box control is moved to neutral position.

4. In a dictating machine, in combination, a frame, a sound-box mounted to travel along said frame and movable transversely of said frame to assume record-engaging and record-nonengaging positions, means for imparting transverse movement to said sound-box, a record-ejector, a lock for said record-ejector, actuating means on the frame having a cam connection with said lock for determining the relation of said lock to said record-ejector, and means responsive to the transverse movement of said sound-box for effecting movement of said actuating means to permit operation of said record-ejector only 30 when said sound-box assumes its record-nonengaging position.

JOSEPH M. LUCARELLE.
JOHN E. RENHOLDT.
